UNITED STATES PATENT OFFICE.

CHARLES EDWARD HAVILAND, OF LIMOGES, FRANCE.

DESIGN FOR A COVER-DISH.

SPECIFICATION forming part of Design No. 27,377, dated July 20, 1897.

Application filed June 5, 1897. Serial No. 639,611. Term of patent 7 years.

To all whom it may concern:

Be it known that I, CHARLES EDWARD HAVILAND, a citizen of the United States, residing at the city of Limoges, in the Republic of France, have invented and produced a new and original Design for a Cover-Dish or Similar Article of a Table-Service, of which the following is a specification, reference being had to the accompanying drawings, forming part thereof, and in which—

Figure 1 is a top view of a cover-dish bearing my design. Fig. 2 is a side elevation of same, and Fig. 3 is a vertical section of a portion of same on the dotted line 3 3 of Fig. 1.

15 The leading features of my design consist of the ornamental form and configuration of the dish and its cover, substantially as illustrated in the accompanying drawings.

In the drawings, A designates the body of 20 the dish, and B the cover therefor, the said cover having a raised ornamental center C, bearing a handle D. The rim of the cover B bears the ornamental band E, having at definite points the ornate figures F, and inward

beyond said band E the cover B bears the 25 looped ornamentation G, extending entirely around the cover.

The sides of the body of the dish bear the ornamental band H, ornate figures I, and looped ornamentation J, corresponding with 30 the band E, figures F, and looped ornamentation G of the cover B. The sides of the body of the dish terminate in a well-defined line K, whence the bottom of the dish extends inward and downward on graceful lines 35 to the base L.

At opposite ends of the body A are handles M M.

What I claim is—

The design for a cover-dish; substantially 40 as shown and described.

Signed at Limoges, in the Republic of France, this 13th day of May, A. D. 1897.

CHARLES EDWARD HAVILAND.
